MACARONI

Angelo Ronzoni, Great Neck, N. Y., assignor to Ronzoni Macaroni Co. Inc., Long Island City,
N. Y., a corporation of New York

Application June 5, 1952, Serial No. 20,046

Term of patent 14 years

(Cl. D8—1)

To all whom it may concern:

Be it known that I, Angelo Ronzoni, a citizen of the United States, residing at Great Neck, county of Nassau, State of New York, have invented a new, original, and ornamental Design for Macaroni, of which the following is a specification, reference being had to the accompanying drawing, forming part thereof.

In the drawing:

Fig. 1 is a perspective view of the macaroni showing my new design,

Fig. 2 is an end view of the macaroni shown in Fig. 3,

Fig. 3 is a side view of the macaroni shown in Fig. 1,

Fig. 4 is another view thereof in slightly turned position,

Fig. 5 is an end view of the macaroni shown in Fig. 4, and

Fig. 6 is a side view of the macaroni shown in Fig. 4 when same is turned cylindrically 90°.

I claim:

The ornamental design for macaroni, substantially as shown.
